Specification for Design.

Patented Dec. 27, 1921.

Application filed July 30, 1920. Serial No. 400,245. Term of patent 14 years.

To all whom it may concern:

Be it known that I, WILLIAM J. HAYNES, Junior, a citizen of the United States, residing at Kansas City, in the county of Jackson and State of Missouri, have invented a new, original, and ornamental Design for a Vacuum-Cleaner for Erasers, of which the following is a specification, reference being had to the accompanying drawing, forming part thereof.

Figure 1 is an elevation of one side of my new design. Fig. 2 is an elevation of another side of the same, and Fig. 3 is a top view of the same.

I claim—

The ornamental design for a vacuum cleaner for erasers, as shown.

WILLIAM J. HAYNES, JUNIOR.
